UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

CAR TRUCK.

Application filed March 4, 1924. Serial No. 696,745.

To all whom it may concern:

Be it known that I, HARRY M. PFLAGER, a citizen of the United States, residing at St. Louis, Missouri, have invented a certain new and useful Improvement in Car Trucks, of which the following is a specification, such as will enable others skilled in the art to which it appertains to make and use the same.

10 My invention relates to railway car trucks and consists in an improved cross bolster and center bolster assembly in six wheel trucks.

15 The object of my invention is to prevent relative movement of the cross bolsters and center bolster in the event of collision or any other abnormal shock which must be absorbed by these members. In the event of such a shock, the center bolster may attempt to shift horizontally or to rise off 20 of the truck, and I desire to guard against either of these movements.

25 Preferably the anti-shifting elements are formed integral upon the bolsters so as to minimize size and cost and eliminate loose play or failure such as is likely to result from riveted or bolted connections.

30 In the accompanying drawings which illustrate my invention—

35 Figure 1 is a top view of a six wheel truck to which my invention is applied in a preferred form.

Figure 2 is a vertical side elevation of the truck sectioned in part to more clearly illustrate the invention.

40 Figures 3 and 4 are detailed sections corresponding to the sectioned portions of Figure 2 and illustrating modifications of my invention.

45 Figure 5 is a similar detail section of the preferred construction.

The truck includes the usual wheels 1, axles 2, journal boxes 3, equalizers 4, frame 5 supported on the equalizers through 45 springs 6, and a spring plank 7 swung from the frame by links 8. Spaced cross bolsters 9 are carried by the frame through springs 10, spring plank 7 and links 8. A center bolster 11 is mounted upon cross bolsters 9 and comprises a center plate support portion 12 and horizontal legs 13 extending from the center plate portion outwardly and over the cross bolsters.

To more securely hold the center bolster and cross bolsters in assembled position, 55 these members are provided with interengaging elements adapted to resist displacement of the members in the event of collision or other shock. In the preferred form illustrated in Figures 1 and 2, these elements take the form of angular flanges or lugs 14 on cross bolsters 9 and horizontal flanges or lugs 15 formed on the feet of legs 13. Each of the flanges 14 extends longitudinally of its respective cross bolster for a relatively short distance and extends upwardly and inwardly toward the other flange. These flanges are arranged in pairs, as illustrated, and cooperate to form an inverted T-slot or recess in which 70 the horizontal flanges 15 on the center bolster may be slid by movement of the center bolster transversely of the truck and longitudinally of the cross bolsters. After being so assembled, the parts are retained 75 against reverse disassembly movement by means of bolts 19.

Obviously, this construction of the cross bolster and center bolsters provides interengaging elements which effectively resist 80 any relative movement of the bolsters longitudinally of the truck or vertically of the truck.

In the modified construction shown in Figure 3 the horizontal top surfaces of 85 cross bolsters 16 are provided with openings 17 into which fit lugs 18 of the center bolster, and in the modified construction shown in Figure 4, the feet of the center bolster are provided with spaced depending lugs 20 which straddle cross bolster 21 which may be recessed as indicated so as to afford engagement with lugs 20 transversely of the truck as well as longitudinally of the truck. In each of these modified constructions, the bolster will be connected by bolts corresponding to bolts 19 and while these bolts will be sufficient to resist ordinary shifting stresses, they will not be called upon to resist extraordinary stresses resulting from abnormal conditions.

In all of these constructions, I prefer to form the interengaging elements integrally with their respective bolsters, but the broad idea may be embodied in suitable elements 105 otherwise provided on the bolsters.

Other modifications in my invention may be made without departing from the scope thereof as expressed in the following claims.

I claim:

5. 1. In a car truck including a frame, cross bolsters carried by said frame, the tops of each of said cross bolsters being provided between its sides with vertical surfaces facing each other and extending transversely 10 of the truck, a center bolster supported on said cross bolsters, and projections on said center bolster each extending downwardly between a pair of said opposing cross bolster surfaces.
15. 2. In a car truck including a truck frame, spaced cross bolsters carried by said frame, a removable center bolster supported on said cross bolsters, and interengaging elements integral with said cross bolsters and center 20 bolster respectively to prevent relative movement thereof vertically of the truck.
25. 3. In a car truck including a truck frame, spaced cross bolsters carried by said frame and provided on their upper surfaces with undercut flanges extending transversely of the truck, and a center bolster carried by said cross bolsters and provided with integral projections extending into said recesses to prevent shifting of said center 30 bolster longitudinally or vertically of the truck.
35. 4. In a car truck including a truck frame, spaced cross bolsters carried by said frame, each provided with spaced recesses in its upper face, a removable center bolster comprising a center plate and legs extending horizontally from said center plate over said cross bolsters and terminating in integral 40 projections insertable into said recesses in one horizontal direction and held thereby against movement in other horizontal directions and in vertical directions and removable means preventing reverse movement of said projections along the line of their insertion.
45. 5. In a car truck including a truck frame, spaced cross bolsters carried by said frame, each provided on its upper face with an inverted T-slot of restricted length, a center 50 bolster comprising a center plate and extensions each terminating in horizontal flanges adapted to be inserted laterally into one of said slots to be held against vertical and longitudinal movement relative to said cross bolsters.
55. 6. In a car truck including a truck frame, spaced cross bolsters carried by said frame, each provided on its upper face with an inverted T-slot of restricted length, a center bolster comprising a center plate and extensions each terminating in horizontal flanges adapted to be inserted laterally into one of said slots to be held against vertical and longitudinal movement relative to said cross bolsters, and removable means preventing 60 transverse movement of said cross bolster.
65. 7. In a one-piece cast truck bolster having a horizontal top surface, integral angular flanges extending longitudinally of said bolster for a relatively short distance 70 and extending upwardly therefrom and toward each other, the space between said flanges being open at the ends thereof to permit the lateral insertion of a flange engaging member between said flanges.
75. 8. In a one-piece truck center bolster, a center plate having horizontal legs extending therefrom to support said center plate from truck cross bolsters, each of said legs terminating in a downwardly extending 80 portion provided with horizontal flanges extending from said portion toward and away from the center plate.
85. 9. In a one-piece truck center bolster, a center plate having horizontal legs extending therefrom to support said center plate from truck cross bolsters, each of said legs terminating in a downwardly extending portion of I-shaped cross section, and a horizontal projection on each I-flange at the 90 end of the latter and extending forwardly and rearwardly of the I-web beyond the I-flanges.

In testimony whereof I hereunto affix my signature this 23 day of February, 1924.

H. M. PFLAGER.
